UNITED STATES PATENT OFFICE.

PAUL R. JORDAN, OF INDIANAPOLIS, INDIANA.

VENTILATOR-COWL.

1,325,947.

Specification of Letters Patent. Patented Dec. 23, 1919.

Application filed June 3, 1916. Serial No. 101,491.

To all whom it may concern:

Be it known that I, PAUL R. JORDAN, a citizen of the United States, residing at Indianapolis, in the county of Marion and 5 State of Indiana, have invented a new and useful Ventilator-Cowl, of which the following is a specification, reference being had to the accompanying drawings and to the letters and figures of reference marked 10 thereon.

This invention relates to a cowl or hood of the type that is designed to be used on the top of a ventilator pipe or conduit or upon a chimney, the invention having reference 15 more particularly to the type of cowl that is provided with a vane to be acted on by air currents for adjusting the cowl.

An object of the invention is to provide an improved cowl of the above-mentioned 20 character that shall be so constructed as to be highly sensitive to air currents in order to be reliably automatic in action to prevent the air currents entering the ventilator top.

Another object is to provide an improved 25 ventilator cowl of simple and inexpensive construction which shall be reliable, strong and durable in use.

A further object is to provide a ventilator cowl of improved construction that may be 30 rapidly manufactured without requiring expensive machine work or accurately fitted parts, an aim being to enable the workman to readily balance the cowl structure after securing the various parts thereof together.

35 With the above-mentioned and other objects in view, the invention consists in an improved adjustable cowl or hood provided with an improved vane or tail piece for controlling the position of the cowl or hood 40 with respect to the air currents, the invention including improved means for balancing the weight of the vane or tail piece; and the invention consists also further in the novel parts and combinations and arrangements 45 of parts as hereinafter particularly described and further defined in the accompanying claims.

Referring to the drawings, Figure 1 is a side elevation of the improved ventilator 50 cowl or hood; Fig. 2 is a top plan of the improved cowl or hood; Fig. 3 is a fragmentary section on the line A A of Fig. 2 on an enlarged scale; Fig. 4 is a vertical section of the cowl or hood on the plane of line 55 A A of Fig. 2; Fig. 5 is a horizontal section on the line B B of Fig. 1; Fig. 6 is a

fragmentary sectional elevation approximately on the line C C of Fig. 5; Fig. 7 is a front view of a balancing weight preferably forming a part of the improved cowl 60 or hood, and Fig. 8 is a fragmentary sectional elevation on the line D D of Fig. 4 on an enlarged scale.

On the different figures of the drawings corresponding reference characters refer to 65 like elements or features of construction herein referred to in detail.

A practical embodiment of the invention may be variously adapted to be supported on the building that is to be equipped with 70 the cowl or hood, the base portion of the cowl in the present case being illustrated as being supported directly upon the roof 1 of a barn and therefore, a base 2 is provided which is adapted to be readily fitted to the 75 roof where required. The base has a shoulder 3 from which a neck 4 extends, the latter preferably having an external bead 5. The base and its neck comprises a duct, and the improved cowl structure includes a tubular 80 base section 6 which is connected to the neck 4. Preferably the base 2 is provided with braces 7 secured to the shoulder 3 and the neck 4, the braces extending upward against the exterior of the base section 6. Cross 85 bars 8 and 9 are secured to the inner side of the tubular section 6 and vertically support a pivotal shaft 10, the shaft being secured to the cross bars, preferably by means of set-screws 11 and 12. The hood part of 90 the improved structure is elbow-shaped so as to have a vertical portion 13 and a horizontally disposed portion 14, the vertical portion having an open lower end 15 that is placed over the upper portion of the base 95 sections 6, the portion 14 having an open end 16 for the escape of the air from the building.

The hood part is provided with an improved bearing appliance which comprises a 100 socket having a base 17 and a cylindrical wall 18, the base being suitably secured on the inner side of the top portion of the hood. Suitable filling 19, such as putty, preferably is placed against the base 17 and preferably 105 a glass bearing plate 20 is placed against the filling, after which a guide tube 21 is inserted into the socket and secured to the wall portion 18 thereof and receives the upper portion of the shaft 10 which supports 110 the base of the socket and more directly supports the bearing plate 20, the latter being

preferably applied for permitting the hood to freely rotate on the shaft. The socket 14 preferably is secured to the portion 14 of the hood by means of a rivet 22 that extends 5 through the base 17. The lower portion of the hood is guided by means of a guide bar 23 that is secured to the inside of the portion 13 and is rotatably guided on the shaft 10, the shaft being provided with a stop pin 24 10 above the guide bar to prevent the hood from being blown off of the shaft, but permitting the hood to freely rotate on the shaft.

The improved vane or tail piece comprises a blade 25 that is provided with a base flange 26 which is fixedly secured on the top of the portion 14 of the hood and extends outward beyond the open end 16, the blade extending also upward so as to be exposed to the air currents above the hood. The normal rearward end of the blade has two outwardly extending tail portions 27 and 28 thereon that extend divergently each to the other and preferably are 20 curved so as to have concave outer faces. Preferably also the vane has two terminal portions 29 and 30 which are connected to the portions 27 and 28 respectively, and extend convergently rearward and together 25 form a vertical blade portion 31, the portions 29 and 30 preferably being curved so as to have concave outer faces. The tail end of the vane is thus adapted to be very sensitive to light winds and also to be 30 quickly affected when the direction of the air currents change. Two braces 32 and 33 are secured to the opposite portions respectively of the hood part, being secured to the portion 14, and extend upward at an inclination and convergently to the opposite 35 sides of the vane and are secured to the upper portion of the blade 25.

For the purpose of conveniently and cheaply balancing the weight of the vane, a 40 rod 34 is secured to the normal forward portions of the hood and the vane blade, the rod preferably being flat and extending forward a suitable distance. A brace 35 is secured to the portion 13 of the hood and 45 also to the under side of the rod and has a flexible crook portion 36 thereon, a similar crook 37 reversely arranged being secured on the top of the rod, and a balancing weight 38 which preferably is spherical is 50 placed on the rod, the weight having an aperture 39 adapted to receive the rod. The weight is of such size that it should approximately balance the hood on the supporting shaft 10 when placed against the crooks 36 55 and 37, but owing to the rough nature of the parts of the structure which may affect the balancing of the weights, the weight 38 may require adjustment after being placed in position, in which case the crooks are bent 60 either backward or forward until the weight, 65

when in contact with the crooks, accurately balance the cowl or hood structure, after which the rod 34 is twisted beyond the weight so as to form a stop 40 to hold the weight in proper position. The end portion of the rod 34 together with the weight and the brace 35 with the crooks constitute also a plainly-visible pointer to indicate to observers the direction of the wind currents. 70

In practical use, the structurally unbalanced cowl or hood having been accurately balanced on the supporting shaft is extremely sensitive to the actions of the air currents, and therefore the ventilation is most effectively accomplished regardless of 75 the shifting winds, and rain and snow are prevented from being driven into the open end of the cowl to cause deterioration of the metal thereof. In case the air is calm so that the cowl becomes stationary and the 80 wind subsequently rises, the vane is promptly affected by the air current so as to properly turn the cowl on its pivot if not in the required position. In case the wind blows toward the terminal edge 31 the 85 force of the air current will in all probability be exerted to a slightly greater degree on either one or the other portions 29 or 30 and accordingly turn the cowl around so that the portions 27 and 28 shall be 90 exposed to the currents; and in case the rising wind strikes either the portions 27 or 28, the vane obviously will be quickly acted upon as will be the case when the wind strikes either the portion 29 or the 95 portion 30. 100

Having thus described the invention, what is claimed as new is:—

1. In a ventilator cowl, the combination of a hood, a vane secured to the hood and having a terminal portion comprising four upright relatively angular outer faces beyond the hood, a separate flexible rod secured to the hood and having a twisted portion at a distance from the hood, a brace 105 secured to the hood and to the rod, and a weight device having an aperture receiving the rod between the twisted portion thereof and the brace and secured thereby in position on the rod. 110

2. In a ventilator cowl, the combination of a hood, a vane having a base secured to the top portion of the hood and extending beyond one side of the hood, the terminal portion of the vane having four upright 115 relatively angular outer faces, a separate flexible rod connected with the vane and secured to the hood, the rod having a twisted portion, a weight device having an aperture receiving the rod, one side of the 120 device being against said twisted portion, a brace secured to the hood and also to the under side of said rod and having a flexible portion engaging the opposite side of said device, and a stop device secured to the up- 125 130

per side of said rod and having a flexible portion engaging said device.

3. In a ventilator cowl, the combination of a hood rotatably supported, one side of the hood being open, a vane having an integral flange that is secured to the top portion of the hood and extends beyond said open side, the terminal portion of the vane having four upright relatively angular outer faces to be impinged upon by an air current coming from either one of the four directions, two of the faces being divergent from the vane and the remaining two convergent from the divergent faces respectively.

4. In a ventilator cowl, the combination of a rotatably supported hood, and a vane secured to the hood, the terminal of the vane having four different faces and comprising two portions that extend divergently 20 each from the other from the body of the vane and two portions that extend convergently each to the other from the divergent portions and are connected together.

In testimony whereof, I affix my signature 25 in presence of two witnesses.

PAUL R. JORDAN.
